UNITED STATES PATENT OFFICE.

MONTRAVILLE M. WOOD, OF ERIE, PENNSYLVANIA, ASSIGNOR OF ONE-HALF
TO THE ERIE COUNTY LIGHT COMPANY, OF SAME PLACE.

ELECTRIC-LAMP HANGER.

SPECIFICATION forming part of Letters Patent No. 397,953, dated February 19, 1889.

Application filed August 23, 1888. Serial No. 283,585. (No model.)

To all whom it may concern:

Be it known that I, MONTRAVILLE M. WOOD, a citizen of the United States, residing at Erie, in the county of Erie and State of Pennsylvania, have invented certain new and useful Improvements in Electric-Lamp Hangers; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 My invention consists in the improvements in electric-lamp hangers hereinafter set forth and described, and illustrated in the accompanying drawings, in which—

Figure 1 shows a side elevation, with parts thereof in section, of my improved hanger with an electric lamp suspended thereon. Fig. 2 shows a like view of same with the lamp unhooked to be lowered down. Fig. 3 shows a view of a modified construction of my device.

Like letters refer to like parts in all the figures.

In the construction of my invention shown, A is a cable adapted to support an electric lamp over the center of a street or at any other desired point. On this cable A, I place a grooved block, B, adapted to slide on said cable, and to the sides of the block B, I secure a stirrup, B', of sufficient strength to support the weight of a lamp. In the lower end of the stirrup B', I provide an insulating-roller, d, which is mounted upon the cross-bolt c, connecting the lower ends of the sides e of the stirrup B' together.

40 In the groove a, in which the cable A operates, I place a hook, C, mounted on a pintle, b, which passes through the block B from side to side. The shank f of the hook C, through which the pintle b passes, is in the form of an eccentric, which the strain of the rope E on the hook C operates to rotate on the pintle b, so as to clamp the cable A firmly in the block B. In the hook C, I secure a small pulley-block, D, through which a small suspending-45 rope, E, passes to the S-shaped hook F, the

upper end, h, of said hook F being secured to the end of the rope E, and the lower end, K, thereof engaging with the ring g in the top of the lamp G. In the center of the hook F, I pivot a tongue, H, adapted to be thrown up 55 by contact with the lower end of the stirrup B', so that the upper end of the hook F will pass by the roller d and allow the lamp G to be lowered down when desired, the opposite end of the rope E, passing over a pulley on 60 the pole, (not shown,) supporting one end of the cable A.

In Fig. 3 I show a modified form of my invention. Instead of the cam-hook C in the block B, I use an ordinary hook, C', in the 65 groove a for supporting the pulley D, and in lieu of clamping the block B to the cable A, to prevent the longitudinal movement of the block B thereon, I secure a rope, I, to the block B by means of a stirrup, J, or in any 70 other convenient manner, which rope is secured to the cable-supporting pole (not shown) at the side of the street opposite to that at which the end of the rope E is secured, so as to withstand the strain of the rope E on 75 the block B.

Having thus fully described my invention, so as to enable others to construct and use the same, what I claim as new, and desire to secure by Letters Patent of the United States, is— 80

1. The combination, in an electrical-lamp hanger, of a block adapted to slide and rest upon a supporting-cable with a hook having a cam-shaped shank pivoted in said block and adapted to be turned on its pintle so as to 85 clamp the supporting-cable against said block, a pulley suspended from said hook, and a rope operating in said pulley for raising and lowering a lamp suspended therefrom, substantially as and for the purpose set forth. 90

2. The combination, in an electric-lamp hanger, of a block adapted to slide and rest upon a supporting-cable, a hook pivoted in said block, and a pulley suspended thereon with a stirrup secured to said block and projecting 95 downward therefrom, a rope passing through said pulley and downward through said stirrup, and an S-hook on the lower end of said rope adapted to support a lamp, and a tongue pivoted to said S-hook so as to close the up-100

per half of said **S**-hook and prevent its engagement with said stirrup when the lamp is being lowered, substantially as and for the purpose set forth.

- 5 3. The combination, in an electric - lamp hanger, of a grooved supporting-block, B, having a hook, C, pivoted therein, with a rigid stirrup, B', secured to said block B and having an insulator, d, in the lower end thereof, 10 a lamp raising and lowering rope, E, passing through a pulley suspended from said hook C and through the stirrup B', an **S**-hook, F, secured to said rope and adapted to suspend a lamp to the stirrup B', and a tongue, H, on 15 said **S**-hook F, adapted to close up against the upper half of the hook F when it is lowered past the lower part of the stirrup B', substantially as and for the purpose set forth.

4. The combination, in an electric - lamp hanger, of a grooved block, B, adapted to rest 20 upon a supporting-cable, A, having a lamp-supporting stirrup, B', thereon, with an eccentric clamping-hook, C, pivoted in said block B, a pulley, D, and an **S**-hook, F, thereon, provided with a tongue, H, supported by said 25 hook C, and a lamp raising and lowering rope, E, operating in said pulley D, substantially as and for the purpose set forth.

In testimony whereof I affix my signature in presence of two witnesses.

MONTRAVILLE M. WOOD.
